[57] ABSTRACT

[21] Appl. No.: 382,510

A template has a tab portion in which a special character is formed. The template is insertable into the tape discharge opening of a label-making machine and the tab is positioned in an image-forming station at which the special character is formed on an ultraviolet light sensitive label material when the machine is operated.

INSERT TEMPLATE FOR A LABEL MAKING MACHINE

BACKGROUND OF THE INVENTION

The field of the invention is templates used to form images on ultraviolet light sensitive label materials. More specifically, the invention relates to insert templates for use with disc-shaped templates such as that shown in the copending patent application Ser. No. 226,707 entitled "Disc for Label-Making Machine and Method of Manufacture" which are used in compact label-making machines such as that disclosed in U.S. Pat. No. 3,698,296 entitled "Actinic Label-Making Tool."

Label-making machines such as that disclosed in the above cited patent operate to form characters, or images, on a pressure sensitive adhesive tape by exposing the surface of the tape to ultraviolet light which passes through a template having the desired image formed therein. The template includes a large selection of such characters, and it is bonded to a rigid support member to form a disc. The label-making machine includes a manually operable mechanism which engages the disc and provides a means to position one of the characters in an image-forming station beneath the ultraviolet light source. A standard disc which is typically provided with the machine includes a selection of characters which are chosen because of their wide applicability and may, for example, include the letters of the alphabet, numbers and punctuation marks. However, users often have specific characters, such as company logos and symbols, which they use on their labels, and although it is possible to alter the selection of characters on a standard disc to meet the specific requirements of each user, this approach is economically less practical to all but those users who possess a relatively large number of label-making machines.

SUMMARY OF THE INVENTION

The present invention is a template which may be manually inserted by the user into the image-forming station of a label-making machine. A blank is formed on the disc used in the machine and this blank is manually positioned in the image-forming station by rotating the disc in the usual manner. The insert template has the desired character formed thereon and is inserted into the image-forming station through the opening from which the finished label is dispensed. The insert template is shaped such that the character formed therein is guided into the blank on the disc and is properly positioned between the ultraviolet light source and label material to orient the resulting image on the label.

A general object of the invention is to provide an insert template which may be manually inserted into a label-making machine to form a character on the sensitized label material. The insert is formed from an opaque sheet of heat conductive material which is bonded to a sheet of transparent backing material. The character is formed by removing portions of the opaque heat conductive material and the periphery of the insert template is shaped to fit into the opening in the label-making machine. A handle portion is formed so that the insert template may be easily inserted and removed from the image-forming station, and means

are provided to guide the insert template into a blank.

Another object of the invention is to adapt a label-making machine and associated disc to receive an insert template. The disc is formed by bonding a sheet of heat conductive material and associated transparent backing material to a rigid support member which is preferably made of a strong, light weight material. A band of windows are formed in the rigid support member and a character is formed in the sheet of heat conductive material directly beneath each window. The blank position is formed in the disc by removing a portion of the heat conductive sheet material and associated backing material beneath one of the windows.

10 When the blank is rotated into the image-forming station beneath the light source, the insert template may be inserted into the cut away portion and guided thereby to properly align the character formed on the insert beneath the window in the rigid support member.

20 Another object of the invention is to provide a relatively inexpensive means of forming selected characters on label material. Instead of replacing the standard disc with one which is adapted to suit the particular needs of each user, a blank is formed in each standard disc and a relatively inexpensive insert template is provided. Each user may, therefore, have his own particular logo or symbol formed on the insert template instead of purchasing a custom made disc.

25 30 The foregoing and other objects and advantages of the invention will appear from the following description. In the description reference is made to the accompanying drawings which form a part hereof, and in which there is shown by way of illustration a preferred embodiment of the invention. Such embodiment does not necessarily represent the full scope of the invention, however, and it is anticipated that changes can be made to the described embodiment that will be within the scope of the present invention.

BRIEF DESCRIPTION OF THE DRAWINGS

FIG. 1 is a side elevation view of the label-making machine to which the present invention is applied,

45 FIG. 2 is a partial side view of the machine in FIG. 1 with parts cut away to show the image-forming station therein,

50 FIG. 3 is a partial top view of the machine in FIG. 1 with parts cut away to show the relationship of the insert template and disc when the insert template is positioned in the image-forming station,

FIG. 4 is a bottom view of a portion of the disc which illustrates the insert template positioned in the blank position, and

55 FIG. 5 is a cross section of the invented insert template.

DESCRIPTION OF THE PREFERRED EMBODIMENT

60 Referring to FIG. 1, a label-making machine includes a housing 1 of generally rectangular shape which mounts a cover 2. The housing 1 contains the electronic circuitry and mechanical drive system necessary for performing the label-making process disclosed in the above cited U.S. Pat. The ultraviolet light sensitive tape is stored in a cartridge which is mounted inside the housing 1 and, as labels are made, the tape 3 is automatically advanced through an image-forming station

and out of an opening in the side of the housing, indicated generally as 4. A cutoff mechanism 5 is mounted to the side of the housing 1 and as the tape 3 is advanced from the image-forming station it passes through the cutoff mechanism 5 where it is cut to the desired length by depressing a cutoff lever 6.

Referring to FIGS. 1, 2 and 3, the label-making machine includes a tape advance wheel 7 which is mounted to the back side of the housing 1 and which connects through a drive shaft 8 to a tape feed drive wheel 9. The drive wheel 9 bears against the bottom surface of the tape 3 and provides a means of manually advancing it. A spacing selector wheel 10 mounts to the front side of the housing 1 and it connects through an automatic feed drive mechanism (not shown in the drawings) to the drive shaft 8. The feed drive mechanism automatically advances the tape 3 each time the image-forming process is initiated by an amount determined in part by the setting of the spacing selector wheel 10 and in part by the length of the proportional spacing slot. Finally, a character selector knob 11 is rotatably mounted to the label-making machine and extends upward through an opening in the cover 2, and it is coupled to a disc 12 which is identical to that disclosed in the above cited copending patent application. The disc 12 is mounted directly beneath the cover 2 and it includes a template having a selection of characters formed in a band around its periphery. By rotating the character selector knob 11, one of these characters is positioned in an image-forming station directly above the sensitized tape 3. An operating lever 13 is pivotally mounted to the side of the housing 1, and when depressed, it initiates the image-forming process.

The image-forming process is a timed exposure of the top surface of the sensitized tape 3 to ultraviolet light. The light is generated by a light source 14 which is located directly above the image-forming station in an enclosure 15 which has a rectangular opening 16 formed in it directly beneath the light source 14. The disc 12 bears against the bottom surface of the enclosure 15 and the character to be formed is aligned in the image-forming station directly beneath the opening 16. The tape 3 is dispensed from its cartridge by the tape feed drive wheel 9 and passes beneath the disc 12 through the image-forming station. During normal operation, the disc 12 is rotated to orient a selected character in the image-forming station, however, when the insert template is to be used, a blank, or cut away portion of the disc 12 is rotated into the image-forming station.

As disclosed in the above-cited copending application, the disc is made from a relatively thick aluminum support member 17 in which windows are formed in a band around its periphery. A template 18 formed of a sheet of brass bonded to a sheet of transparent backing material is bonded to the underside of the support member 17. The blank portion is formed in the disc 12 by cutting away a portion of the template 18 beneath one window by making a pair of radial cuts. The blank portion thus includes a pair of spaced, radially directed side edges 19 which are to serve as guideways for the insert template.

The insert template indicated generally by the reference number 20 is formed by bonding a mask 21 made of a sheet of heat conductive material such as brass to a sheet of transparent backing material 22 such as a fluorocarbon polymer. The thickness of the mask 21,

backing material 22 and an adhesive 23 are chosen such that the total thickness of the insert template 20 is substantially the same as the thickness of the template 18 on the disc 12. In the preferred embodiment, both the mask 21 and backing material 22 are 5 mils thick.

The insert template 20 is constructed by first applying a layer of pressure sensitive adhesive 23, such as a vinyl-acrylic adhesive, to a sheet of backing material 22. A liquid or dry film photo resist 24 is then applied to the top surface of the brass sheet 21 and the backing material 22 is bonded to its bottom surface. The resulting laminate is placed under a photographic film (not shown) with the photo resist side of the brass sheet 21 in direct contact with the emulsion side of the film. A vacuum is applied and the brass is then exposed to light. The exposed surface is developed and submerged in an etchant such as ferric chloride which removes those portions of the brass sheet which are not protected by the developed photo resist. The outline and the desired "special" character are thus formed and the insert template 20 is completed by cutting away the selvage material.

The shape of the insert template 20 is designed to facilitate its insertion into and removal from the image-forming station and to properly locate the character formed therein beneath the light source 14. More specifically, the character is formed on a tab portion 25 which is defined by a pair of tapered margins 26 that engage the guideways 19 when the insert template 20 is fully inserted. Also, the insert template 20 includes a handle portion 27 which is substantially wider than the tab 25 to both facilitate handling of the insert template 20 and to define a pair of bearing edges 28. The bearing edges 28 are disposed to either side of the tab portion 25, and when the insert template 20 is properly positioned, the bearing edges 28 engage the outer surface of the cutoff mechanism 5 to limit further motion. The tab 25 is thus positioned within the blank formed on the disc 12 and in bearing engagement with the underside of the aluminum support member 17. The proper circumferential alignment of the character is insured by the original mating engagement of the tapered margins 26 with the guideways 19, while the proper radial alignment is insured by the engagement of the bearing edges 28 with the cutoff mechanism 5.

It should be apparent to those skilled in the art that a number of variations can be made in the preferred embodiment of the invention described and shown herein without departing from the spirit of the invention. For example, the handle portion 27 need not extend laterally on both sides of the tab portion 25, but instead, may extend in one direction to provide one bearing edge 28. Also, the handle portion 27 may include additional layers of material to provide further rigidity and durability.

I claim:

1. In a label-making machine which includes a template having a plurality of characters and a blank portion, a mechanism for selectively positioning said characters in an image-forming station, an ultraviolet light source, and means to feed label material through the image-forming station for forming an image on said label material, the improvement comprising:
an insert template that is manually insertable into said image-forming station when the blank portion

of the disc is positioned in the image-forming station, said insert template including:
a tab portion which is of substantially the same thickness as said template and which includes a special character formed therein and a sheet of heat conductive metal bonded to a sheet of transparent fluorocarbon polymer backing material and portions of said heat conductive metal sheet are removed to form said special character; and
a handle portion which is substantially wider than said tab portion to define a bearing edge which engages said label-making machine when the character formed on said tab portion is fully inserted in

said image-forming station.

2. The structure as recited in claim 1 in which the blank portion in said template is formed with a pair of spaced radial side edges which define guideways, and the margins of the tab portion are tapered to engage and mate with the guideways when the insert template is properly inserted in said image-forming station.

3. The structure as recited in claim 2 in which said heat conductive metal is brass and the portions thereof which are removed to form said special character are removed by an etching process.
